(57) **CLAIM**

The ornamental design for a patient care assembly component as shown and described.

DESCRIPTION

FIG. 1 is a front, bottom, and right side perspective view of a patient care assembly component showing our new design; FIG. 2 is a rear, top, right side perspective view thereof; FIG. 3 is a front side elevational view thereof; FIG. 4 is a rear side elevational view thereof; FIG. 5 is a left side elevational view thereof; FIG. 6 is a right side elevational view thereof; FIG. 7 is a top plan view thereof; and, FIG. 8 is a bottom plan view thereof.

In the drawings, the broken lines are for the purpose of illustrating portions of the patient care assembly component which form no part of the claimed design.
